DOORCHECK

Gustav A. Carlson, Chicago, Ill., assignor to The
Boye Needle Company, Chicago, Ill., a cor-
poration of Illinois

Application September 3, 1932. Serial No. 631,718

3 Claims. (Cl. 16—84)

This invention relates to a door check. However, the invention is applicable to other uses and, while the invention is described herein in connection with a door, it will be understood that the invention may be used in conjunction with other types of closures.

An object of the invention is to provide improved means for cushioning the closing of a door or the like and means for automatically resetting the cushioning apparatus every time that the door is opened. The invention is particularly useful in connection with screen doors which are urged toward the door frame by springs. Other specific objects and advantages will appear as the specification proceeds.

The invention is illustrated, in its preferred embodiment, in the accompanying drawings, in which—

Fig. 1 is a view in elevation of apparatus embodying my invention and shown applied to a door and door frame, the air tube being shown in longitudinal section and the section being taken as indicated at line 1 of Fig. 2; Fig. 2, a top plan view; Fig. 3, an enlarged sectional view, the section being taken as indicated at line 3 of Fig. 1; Fig. 4, a broken view similar to Fig. 2 but showing the door in partially open position; Fig. 5, a transverse sectional view, the section being taken as indicated at line 5 of Fig. 2; Fig. 6, a detail sectional view, the section being taken as indicated at line 6 of Fig. 2; and Fig. 7, a transverse sectional view, the section being taken as indicated at line 7 of Fig. 6.

In the illustration given, A designates a door frame provided with a door jamb A'; and B designates a door hinged to the frame. The door is illustrated as provided with a screen B'; and the door B is drawn toward the frame A by a tension spring 10.

In the use of the specific embodiment illustrated, the door jamb A' may be cut away at 11, if desired, and a bracket or keeper 12 secured to the frame A. However, if desired, the keeper 12 may be secured directly to the jamb A'. The bracket 12 is provided with a horizontal flange 13 to which is secured a pin 14. About the pin is rotatably carried a roller 15.

Secured to the door B is a bracket member 16 carrying a tube 17 which is integrally formed therewith. The tube 17 is provided at its inner end with an opening 18 and at its opposite open end is threaded to receive cap 19. The cap 19 is provided with an opening 19a. The cap 19 is preferably provided with an apertured boss 20 adapted to receive and guide the valve stem 21.

Secured to the inner end of the valve stem 21 is an air-tight head 22 which may be of any suitable construction.

If desired, the tube 17 may be provided with a check valve of any suitable construction. As shown more clearly in Figs. 1 and 3, a metal disk 23 is secured within the inner end of tube 17 by means of the split spring 24. The disk 23 is cut away along its central portion to provide a resilient arm 25 which carries a valve disk 26. The closure disk 26 is provided centrally with a tiny orifice 27. With this construction, the valve 26 permits a large intake of air through the opening 18 as the stem 21 is withdrawn but during the compression stroke seats 70 tightly against the opening 18 and permits the escape of air only through the tiny orifice 27.

Secured to the outer end of the stem 21 is a catch plate or slotted head 28. The head may be secured to the stem 21 in any suitable manner. In the illustration given, the head 28 is provided with attachment lugs or ears 29 which are clamped about a reduced portion 30 of the valve stem. As shown more clearly in Figs. 1 and 4, the catch plate or head 28 is provided with a slot 31 which tapers outwardly toward the open end 32. The outer end of the plate is provided with a curved cam surface 33 adapted to engage the roller 15. Below the cam 32 and extending forwardly thereof is a lip extension 34 adapted to engage the roller 15 and to guide it into the slot 31. It will be noted that the slot 31 is somewhat sector-shaped so as to permit the swinging of the head about the stud or roller as the door moves toward or away from 90 these members.

In the operation of the device, with the door in closed position, as shown in Fig. 1, when the door is opened, the roller 15 engages the upper jaw of the head and causes the valve stem 21 to be retracted. The outward swinging of the door, as illustrated in Fig. 4, finally causes the stud to clear the upper point of the head and leaves the stem 21 in fully withdrawn position. During this movement, the check valve 26 permits the full intake of air into the chamber 17, the air on the upper side of the valve head 22 being expelled readily through the opening 19a. When the door is closed, the lip extension 34 is brought into contact with the stud 105 14 and guides it into the slot 31. If desired, the roller 15 may first contact with the cam surface 32 and be guided thereby into the mouth of the slot. The piston stem is then urged inwardly so as to force the piston head 22 toward the open- 110

ing 18. The pressure causes the piston head 26 to seat against the lower portion of the tube 17 and permits escape of air only through the tiny orifice 27. This action results in a cushioning of the stem and allows the door to come against the door jamb slowly and silently.

While the door check has been illustrated as provided with a check valve, it will be understood that this may be dispensed with, if desired, and the tube 17 provided merely with a tiny orifice instead of the large orifice 18. Other changes in the details of construction may readily be made without departing from the spirit of the invention.

15 The foregoing detailed description has been given for clearness of understanding only, and no unnecessary limitations should be understood therefrom, but the appended claims should be construed as broadly as permissible, in view of 20 the prior art.

I claim:

1. In combination with a door and door frame, a stud supported by one of such members in spaced relation thereto, a stationary support secured to the other member, a stem reciprocally guided in said support, means carried by said support for cushioning the rearward movement of said stem, and a head secured to the outer

end portion of said stem and provided with a laterally extending slot, said slot having an open end adapted to receive said stud.

2. In combination with a door and door frame, a stud supported by one of said members in spaced relation thereto, a stationary support carried by the other member, a stem reciprocally guided therein and aligned with said stud, means for cushioning the rearward movement of said stem, and a head secured to the forward end 85 of said stem and having a tapered laterally extending slot therein, said head being also provided with a lip extension on the inner side of said slot.

3. In combination with a door and door frame, 90 supports carried by said door and door frame, a stem reciprocally guided in one of said supports, means associated with said last mentioned support for cushioning the rearward movement of said stem, and releasable interlocking members 95 carried by the other support and by the free end of said stem, one of said interlocking members comprising a stud and the other interlocking member comprising a head having a laterally extending slot, said slot having an open 100 end adapted to receive said stud.

GUSTAV A. CARLSON.
